UNITED STATES PATENT OFFICE.

JOHN A. PASKAL, OF LOS ANGELES, CALIFORNIA.

SHOE-SOLE MAT.

Application filed May 25, 1926. Serial No. 111,556.

My invention is a shoe sole brushing mat, adapted to be attached underneath the running board of an automobile or underneath the step, the mat being slidable in and out of 5 a suitable housing.

Another object of my invention is to utilize a mat which may be slid in and out of a suitable housing or casing, this being attached preferably to the running board of 10 a vehicle and below same. The mat may be held in the tray so that it may be removed for cleaning or replacement.

Another object of my invention is to retain the mat device and the tray to which it 15 is attached within the housing by means of a latch and having a spring normally tensioned to force the tray outwardly for use after releasing of the catch.

My invention will be more readily understood from the following description and drawings, in which;

Fig. 1 is a perspective view of a construction of my invention, utilizing a mat and scraper in connection therewith, the mat and 25 scraper being slidable as a unit in a housing underneath a running board;

Fig. 2 is a horizontal section on the line 8—8 of Fig. 1, in the direction of the arrows, illustrating the housing in section;

Fig. 3 is a cross sectional view on the 30 line 9—9 of Fig. 1, in the direction of the arrows.

In the construction of Figs. 1, 2 and 3 the running board of a vehicle is indicated by 35 the numeral 40, having the housing or casing 41 secured below same, this casing being open and having side walls 42, a rear wall 43 and a front wall 44 having extensions 45 over the edge of the running board 40 and backwardly bent flanges 46 engaging the top of the running board. Lugs 47 or the like are utilized to attach the housing to the running board.

A slidable tray or the like designated generally by the numeral 48 has front, back and side walls designated respectively by the numerals 50, 51 and 52 and 53 and a base wall 54. A mat 55 is secured in such tray, the mat being of such height that it will 50 slide through the elongated opening 56 in the front plate 44 and into the housing.

The tray is also formed with an extra side wall 57 against which is secured a scraper bar 58 having a sharp apex 59 for 55 scraping the mud. It is preferable to leave an elongated slot 60 in the base of the tray

so that mud may drop through. If desired the scraper bar and the wall of the tray may be formed integral.

Slide bars 61 are secured to the side of the 60 tray or formed integral therewith and slide in grooves 62 formed in the side of the housing. A pair of rods 63 are illustrated in Fig. 2 as being secured to the rear wall of the tray and slide through apertures 64 in 65 the inner wall of the housing. Compression springs 65 are coiled around these rods, bearing on the inner wall of the housing and on the inner wall of the tray and normally tending to thrust the tray outwardly. 70 A catch of any suitable type and indicated as the catch 18 is secured to the housing and by means of the hook is adapted to engage the front plate 50 of the tray and hold the brush and scraper in their innermost position. 75

With this construction of combined mat and scraper mounted in a tray, it is only necessary to operate the catch to release the tray when same will be forced outwardly by 80 the compression springs 65, the tray being guided in its outward movement by the construction of same and by means of the rods 63. When thrust inwardly these rods are intended to extend underneath the body of 85 the vehicle.

It is obvious that the mat will be made of proper size for the tray, and will be readily removable for cleaning or replacement, and also the scraper bar could be made 90 removable so that on becoming dull, could be removed and sharpened or a new bar installed as a replacement.

Such changes may be in the general construction or specific details. These changes 95 however, will be within the spirit of my invention as set forth in the description, drawings and claims.

Having described my invention, what I 100 claim is:

1. A shoe mat comprising in combination a housing having means to secure same to a step or the like, a structure supporting a mat slidable in the housing, springs in the housing tensioned to force said structure outwardly, a latch to hold such structure in a housed position, and the mat holding structure having a plurality of rods attached to the inner end thereof, said rods being slid- 105 able through the back of the housing.

2. A shoe mat comprising in combination a housing having means to secure same un- 110

derneath a step, a structure supporting a mat, a pair of rods attached to the inner part of said structure, said rods being slidable through the back of the housing, springs on 5 the rods tensioned to force the structure out of the housing, and a latch to retain the structure within the housing.

3. A shoe mat comprising in combination 10 a rectangular housing having means to secure same underneath a step, a rectangular frame having a mat therein, a pair of rods attached to the inner part of the frame and slidable through the back of the housing, springs on said rods tensioned between the 15 back of the housing and the inner part of the frame, said springs forcing the rectangular frame out of the housing, and a slidable latch on the housing having a spring, said latch engaging the frame to hold the frame 20 in the housing.

4. A shoe mat comprising in combination 25 a housing having a front wall with extensions upwardly therefrom, said extensions engaging over the edge of a running board, the housing having side and back walls,

means to secure the housing underneath the running board, a frame slidably mounted in the housing having a mat, a plurality of rods attached to the rear side of the frame and slidable through the rear wall of the housing, springs tensioned between the rear wall of the housing and the inner wall of the frame and normally pressing the frame out of the housing, and a latch on the housing 30 engaging the frame to retain same in the 35 housing.

5. In a shoe mat the combination of a housing having means to secure same underneath a running board, a frame slidable in the housing having a mat, a spring in the 40 housing pressing the frame outwardly, a latch slidably mounted on the housing and having a hook shaped catch to engage the frame to retain same in the housing, said latch having a spring to retract same to firmly engage 45 and hold the frame.

In testimony whereof I have signed my name to this specification.

JOHN A. PASKAL.
